UNITED STATES PATENT OFFICE.

ROBERT S. HAUN, OF AMES, IOWA.

STANCHION-RELEASE.

1,102,150.

Specification of Letters Patent. Patented June 30, 1914.

Application filed April 5, 1913. Serial No. 759,107.

To all whom it may concern:

Be it known that I, ROBERT S. HAUN, citizen of the United States, residing at Ames, in the county of Story and State of Iowa, have invented certain new and useful Improvements in Stanchion- Releases, of which the following is a specification.

This invention relates to certain new and useful improvements in cattle stanchions, and has particular reference to such improvements whereby all the cattle may be simultaneously released from the stanchion at one operation of the device.

A further object of the invention contemplates the provision of specially devised trip mechanism arranged adjacent each stanchion; the simultaneous operation of the said mechanism adapted to automatically unlock the stanchion arms for quickly releasing the cattle from the several stalls in connection with which the invention is employed.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an elevation of a device constructed in accordance with my invention; Fig. 2 is a section on line 2—2 of Fig. 1; Fig. 3 is a detail elevation of one of the clamps; Fig. 4 is a detail perspective view of the fastening means; and Fig. 5 is a similar view of the trigger.

Referring now more particularly to the drawings wherein is illustrated the preferred form of my invention the numeral 1 designates a suitable feed trough through which suitable stanchion posts 2 extend, the latter having partitions 3 secured thereto as at 4 for the purpose of creating any number of stalls desired. The upper extremities of the several posts 2 are connected to a longitudinally extending bar or beam 5 by means of any suitable connection such as is shown at 6. Disposed about midway between the uprights 5 through the medium

of a band 7, I provide a stanchion 8, the same comprising a stationary arm 9 and a pivoted arm 10, the pivot point 11 being at the base of the said two arms 9 and 10. Any suitable means such as a chain 12 60 may be employed for the purpose of suspending the stanchion from one side of the band 7, while a similar chain 13 may be secured in any suitable manner to the trough 1 for rigidly supporting the stanchion in 65 the desired position. Oppositely disposed ears 14 are formed integrally with the stationary arm 9 of the stanchion near the top thereof for the purpose of pivotally mounting a trigger 15, the latter having an opening 16 formed therein through which a pin 17 projecting upwardly from the face of the arm 10 extends. In fastening the pivoted arm 10 of the stanchion to the stationary arm 9 for the purpose of effecting 70 a suitable yoke or stanchion, a slot 18 is formed adjacent the ears 14 and within the stationary arm 9, the pin 17 fitting into the said slot where it is securely held by the trigger 15, the opening 16 of the trigger fitting over the said pin and retaining the latter in proper place within the slot 18 thereby effecting a secure connection between the said two arms 9 and 10.

Having described the manner in which 85 the stanchions 8 are fastened, the detail description of the trip or operating mechanism will now be described. A hand lever 19 is pivotally secured as at 20 to a suitable clamp 21 arranged upon the end post 2 of 90 the device, the said lever 19 being pivotally secured as at 22 to a connecting link 23 in turn pivotally secured as at 24 to a longitudinally extending rod or bar 25, the said bar extending parallel with the cross 95 bar 5 of the stanchion frame. Arranged adjacent the band 7 of the cross bar 5, I provide a suitable clamp 26 having an extension 27 formed integrally therewith and depending from one side thereof as 100 clearly shown in Fig. 3 of the drawings. Pivotally secured to the said extension 27 as at 28 is a bell crank lever 29, one extremity of which is pivotally secured as at 30 to the rod 25 while the other extremity 105 is connected to the trigger 15 through the medium of a chain 31, the point of connection 31 being directly over the hole or opening 16 of the trigger. The construction above recited is duplicated for each 110

stanchion, the several bell crank levers being connected to the bar 25 to effect simultaneous operation thereof by the manipulation of the lever 19.

5 In operation, the pivoted arm 10 of the stanchion is unfastened, whereupon the stanchion is fitted over the neck of the cattle to be confined within the stalls, in which event the said pivoted arm 10 is again fastened by means of the trigger 15. Should a quick release of the confined cattle be desired, the operation of the lever 19 will produce the desired result. By operating the said lever, the bar 25 is laterally moved for 10 simultaneously operating the several bell crank levers 29, which in turn raise the triggers 15 until the pins 17 of the pivoted stanchion arms 10 are withdrawn from the openings 16 of the triggers, whereupon the 15 said pivoted arms 10 are free to swing outwardly from their pivot points 11 thereby 20 effectually releasing the several cattle confined within the several stalls. It will be seen from the above, taken in connection 25 with the accompanying drawings that by eccentrically pivoting the trigger 15 the weighted or larger end of the said trigger will normally fall, and that by providing the said weighted end with the opening 16, 30 the said trigger is normally held with the pin 17 in engagement with the opening 16. By reversing the clamp 26, the extension 27 will depend from the opposite side of the cross bar 5, thus permitting the use or operation 35 of the device from either side of the said bar.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various 40 minor changes in detail of construction, proportion and arrangement of parts may be resorted to, when required, without sacrificing

any of the advantages of my invention, as defined in the appended claims.

Having thus fully described my invention, 50 what I claim as new and desire to secure by Letters Patent, is:—

1. In combination with a plurality of stanchions comprising a stationary and a pivoted stanchion arm having latch means 55 carried thereby to normally maintain said arms incapable of movement one independent of the other, of a support from which the said stanchions are suspended, an adjustable band arranged to embrace said support adjacent each stanchion, an operating lever pivoted to each band, the said levers being pivotally connected, one to each of the said latch mechanisms, and an operating rod to which each lever is connected for actuating the said latch means to simultaneously release said stanchions, as and for the purpose set forth.

2. In combination with a plurality of stanchions comprising a stationary and a 70 pivoted stanchion arm having latch means carried thereby to normally maintain said arm incapable of movement one independent of the other, of a support bar from which the said stanchions are suspended, an adjustable band arranged adjacent each stanchion, the said band being disposed to embrace the said bar, a bell crank lever pivoted to each band, one end of each lever being connected to the latch means of the respective 75 stanchions, an operating rod to which the opposite end of each lever is pivotally connected, a bracket carried by the said support bar, and an operating lever pivotally connected to the said bracket and to the said operating rod for actuating the latter to simultaneously release the said stanchions, as and for the purpose set forth.

In testimony whereof I affix my signature in presence of two witnesses.

ROBERT S. HAUN.
